UNITED STATES PATENT OFFICE.

GEORGE A. KERN, OF BERKELEY, CALIFORNIA.

ORNAMENTAL FOUNTAIN.

Application filed July 6, 1926. Serial No. 120,854.

This invention relates to ornamental fountains.

An object of the present invention is to provide a combined sun-dial and water fountain incorporating a catchment basin or pool providing re-entrant approaches around its perimeter for enabling close approach, between radially directed spray streams, to the dial for convenient reading of its face.

10 An effective embodiment of the invention is illustrated in the accompanying drawing, wherein

Figure 1 is a plan of the structure.

Figure 2 is a side elevation.

15 The present adaptation consists of a suitably ornamented pool or basin 2 from the center of which there extends upward an ornamental column 3 on which is a capital 4 having a sun-dial 5 with the usual gnomon 6.

Around the capital 4 are arranged ornate spouts or gargoyle 7 which discharge to the catchment basin.

It is desirable that a person may approach 25 close enough to the capital to obtain a good inspection of the dial and at the same time

have a safe position between the water streams from the spouts 7. To that end the perimeter of the basin 2 is provided with re-entrant approaches 8 which allow 30 the desired close access or approach to the dial, between the salients 9.

When close in toward the capital the observer has a position between the adjacent radial sprays from the fountain.

It is obvious that the ornate features of the structure may be of unlimited variations.

What is claimed is:

An ornamental fountain structure including a column and a floor base having a water basin wholly surrounding the foot of the column and said basin having salient angles between which are approaches on the floor base toward the column, the latter terminating in a capital at a height above the base to have its top visible to the average individual, and spray gargoyle arranged around the rim of the capital of the column and discharging into the salient angles of 50 the basin.

GEORGE A. KERN.
